LEVER LOCK FOR PRESSING MACHINES

Jacob M. Bernstein and Clarence E. Robertson,
Jr., Pocomoke City, Md.; said Robertson, Jr.,
assignor to said Bernstein

Application August 9, 1951, Serial No. 241,032

9 Claims. (Cl. 223—38)

1

This invention comprises novel and useful improvements in edge folding machines, and more particularly pertains to improvements in means for actuating the folding machines.

This invention relates to improvements in edge folding machines of the type disclosed in Patent No. 2,317,817. In the prior devices, as disclosed in that patent, a forming plate, of the same contour as the article being edged, is movable through aligned complementary openings in a 10 table top and the base plates which are mounted in spaced relation to each other. As the forming plate moves through the openings, the edges of the article are bent transversely thereof around the periphery of the forming plate, and a plurality of holding plates which are movable between the table top and base plate are urged inwardly of the opening by the pusher plate, to thereby fold the upturned edges of the article over on the forming plate. The pressing plate was then foot pedal operated to engagement with the side of the forming plate opposed to the side engaged by the folding plate, to thereby press the edges of the article.

Heretofore, the constant attendance of an operator for the edge folding device was required, not only to maintain the manually operated forming plate and the folding plates in their edge forming position, but also to maintain the foot operated pressure plate in the pressing position. Thus, one operator could not operate more than one edge folding machine at one time.

In the present invention, a common means is provided for moving the forming plate and the folding plate into their edge folding positions, and for releasably locking the plates in that position, to thereby free the operator's hands during the pressing operation. The invention also comprises means controlled by the above mentioned common means, for moving the pressing plate into its pressing position and releasably locking the pressing plate thereto. Thus, an operator may actuate the machine into its edge folding position, and the device will automatically lock in that position, whereby the operator is free to operate other machines while the article is being pressed.

An important object of this invention is to provide a pressing machine which may be set and locked in its edge folding positioning to thereby release the operator for other work while the article is being pressed.

Another object of this invention is to provide common means for actuating the forming plate, the folding plate, and the pressing plate in the

2

operative position to fold and press the edges of the fabric article.

A further object of this invention is to provide a common means for releasably locking the forming plate, the folding plate and the pressing plate in operative position to fold and press the edges of a fabric article, which locking may be easily set and released.

These, together with various ancillary objects are attained by this invention, a preferred embodiment of which is illustrated in the accompanying drawings, wherein:

Figure 1 is a perspective elevational view of an edge folding machine;

Figure 2 is a fragmentary vertical sectional view of the edge folding machine shown in Figure 1, with actuating mechanism thereof shown in edge folding position;

Figure 3 is a fragmentary side elevation view of the pressing machine with the actuating mechanism shown in released position;

Figure 4 is a fragmentary horizontal sectional view, taken upon the plane of the section line 4—4 in Figure 2;

Figure 5 is a fragmentary detail view, taken on the plane of the section line 5—5 of Figure 2;

Figure 6 is a fragmentary side elevational view of a modified form of the edge folding machine, parts being broken away and shown in section to illustrate details of construction; and,

Figure 7 is a fragmentary sectional view taken on the plane of the section line 7—7 of Figure 6.

Reference is now made more specifically to the accompanying drawings, wherein like numbers designate similar parts throughout the various views, and in which the edge folding machine is designated generally by the numeral 10. As is conventional, the folding machine includes a table top 12 and a base plate 14 mounted on a base 16 in parallel spaced relation to each other. An opening 18 of the shape of the article being edged is provided in the table top, and a similar registering opening (not shown) is provided in the base plate. A forming plate 20 formed complementary to the opening 18 is resiliently mounted, as by springs 22 and bolts 24 to the lever 26, for movement into and out of the opening 18. The bolts 24 are rigidly secured to the forming plate 20, and slidably mounted in the lever 26, whereby the forming plate will yieldably press the fabric article into the opening 18 as the lever is swung about its hinge 28. A spring 30 is provided for yieldingly urging the lever and the forming plate out of the opening 18.

3

A pair of folding plates 32 are movably mounted on studs (not shown) carried by the base plate 14 between the table top 12 and base plate 14 for movement inwardly of the periphery of the opening therein, to thereby fold over the edges of the fabric article which are turned or bent transversely of the article as the forming plate is moved into the opening 18. The pusher plate 34 having a transverse ear 36 thereon is provided for moving the folding plates into their edge folding position, the folding plates being yieldingly urged by springs (not shown) into their retracted position.

A pressing plate (not shown) is carried by the arm 38 and is movable into engagement with the underside of the forming plate 20, when the latter is in edge folding position, in response to downward movement of the left hand end of the arm as viewed in Figures 1, 2, 3 and 6. In the devices heretofore developed, the lever 26 was swung downwardly into folding position by means of a handle which was pivotally mounted on the free end thereof, the handle then being pivoted into engagement with the pressure plate to move the folding plates into folding position, the arm 38 being operated by separate foot pedal. The construction thus far described, except for the resilient mounting of the forming plate, is well known, and has been described to facilitate understanding of the operating of the mechanism to be hereinafter set forth.

In the embodiment shown in Figures 1-5, there is provided a latch plate 40, which is pivotally mounted, by bolt 42 on the free end of the lever 26, a nose 44 being provided on the latch member for engagement with the ear 36 on the pusher plate whereby the latter is actuated in response to pivotal movement of the latch member. A finger 46 on the latch member is adapted to engage a keeper 48 on base, and to prevent upward swinging movement of the lever 26 in response to the yielding tension of spring 30, a spring 50 being secured to the latch member on the end thereof remote from the finger 46 and to the bracket 52 on the lever 26, to thereby yieldably urge the latch member out of keeper engaging position.

In order to move and releasably lock the latch member 40 in its keeper engaging position, there is provided a bifurcated press shaped actuating member 54, having a handle 56 thereon, which is pivoted, by bolts 58, at one end thereof to the ear 60 on bracket 52. A finger 62 is provided to limit clockwise swinging movement of the actuating member, as viewed in Figures 2 and 3, in response to the spring 64 which is secured, at one end, by hooks 66 to the actuating member, the other end being secured by eye 68 to the lever 26.

A roller 70 is mounted by bolts 72 between the bifurcated portions of the other end of the actuating member, the roller being adapted to engage first and second contiguous cam portions 74 and 76, respectively, of the latch member 40. The first cam portion 74 is such that when it is engaged with the roller 70, the spring 50 acting through the latch member 40 exerts a substantial tangential force on the actuating member, to yieldingly retain the actuating member in upward position, as is clearly illustrated in Figure 3. As is apparent in Figure 2, the cam portion 76 is so designed that it exerts a substantially radial force on the actuating member 54, when the cam portion is engaged with the roller 70, whereby the spring 50 does not materially tend to urge the actuating member out of its locking position.

shown in Figure 2, and into its inoperative position shown in Figure 3.

The roller 70 is also adapted to engage a roller 78, which is mounted by trunnion 80 on the free end of the presser plate operating arm 38, whereby movement of the actuating member into its locking position pivots the arm 38 in a counter-clockwise direction, to thereby move the presser plate upwardly into pressing position. The arm 38 is yieldingly urged by the spring 82 in a clockwise direction as viewed in Figures 2 and 3, the spring being attached at one end by fastener 84 to the arm, and at the other end by rod 86 to the pusher plate. As is apparent from Figure 2, the roller 78 projects above the arm and serves to releasably retain the actuating member in its locking position, the stiffness of the spring 84 relative to that of the springs 64 and 50 being designed so that the parts function in this manner.

As will be appreciated, movement of the pusher plate 34, to the right, as viewed in Figure 2, causes the folding plates 32 to move inwardly of the periphery of the opening 18 to thereby fold the upturned edges of the fabric article, that movement of the pusher plate also serving to tension the spring 82 and increase the locking action exerted on actuating member 54. Thus, as the latch member is urged into its keeper engaging position by its actuating member, the force exerted by the spring 50 which tends to urge the actuating member into its inoperative position, is decreased, as the roller 70 engages the cam portion 76 simultaneously, the locking action exerted by the roller 78 on the locking arm 38 is increased due to the increased tension on the spring 82 in response to movement of the pusher plate.

The rollers 70 and 78 must obviously be in proper alignment, and, for this purpose, the keeper 48 is preferably attached to or formed integrally with a pair of parallel guides 88 having slots 90 therein, through which fasteners 92 extend to adjustably attach the guides and keeper on the front wall 94 of the base 16. The guides engage opposite sides of the arm and present lateral movement thereof, a set screw 96 being carried by the connected straps 98 on the lower end of the guide for engagement with the lower edge of the front wall 94 to facilitate adjustment of the guide.

In the modified form of the invention shown in Figure 7, the sides of the slot 100 in the front wall 94 adequately guide the arm 38, and the keeper 102 having angulated U-shaped end portions 104 is adjustably mounted by fasteners 106 to the front wall 94.

In Figure 6, there is illustrated a modified form of latch and actuating member which functions in a manner similar to that of the embodiment shown in Figures 1-5. The latch member 108 is pivoted, as at 110, to the free end of the lever 26, the latch member having a nose 112 thereon adapted to engage the ear 36 on the pusher plate, and a keeper engaging finger 114. The latch member is yieldingly urged out of keeper engaging position by spring 116 which has one end secured, as at 118, to the end of the latch member remote from the finger 114 and the outer end secured, as at 120, to the lever 26. An actuating member 122 comprises a pair of spaced plates 124 and a connecting web 126 is pivoted by a bolt 128 to the lever 26, a handle 130 being provided, for obvious reasons. A roller 132 is disposed between the plates and rotatably secured thereto by a pin 134 which roller is adapted to engage contiguous cam surfaces 136, 138 and 140 on the

latch member. The cam surfaces 136 and 138 which respectively correspond to cam surfaces 76 and 74 in the embodiment illustrated in Figures 1-5, are designed to effectuate similar results. Thus, the spring 116 urges the latch member in a direction such that the surface 136 exerts a thrust on the roller 132 which is substantially radial of the axis of rotation of the actuating member, and the cam surface 138 is adapted to exert a force on the roller 132 which is substantially tangential to the axis of rotation of the actuating member, when the respective cam surfaces engage the roller. A spring 116, therefore, is effective to retain the actuating member in its inoperative position, shown in dotted lines in Figure 6, but does not exert a substantial force on the actuating member when the latter is in its locking position, shown in full lines in Figure 6. The cam surface 149 engages the roller 132 when the actuating member and latch member are released, and serves to limit clockwise pivotal movement of the actuating member.

In operation, a fabric article is first positioned over the opening 18 and the lever 26 is moved downward by handle 56 to force the forming plate into the opening and turn the edges of the opening upwardly, the stiffness of the lever counterbalancing the spring 30 being such that a downward pressure on the handle which is sufficient to move the lever is sufficient to move the actuating member relative thereto. The actuating member 54 or 122, as the case may be, is then pivoted in a counter-clockwise direction, shown in the drawings, thereby moving respective latch members 40 and 108 in a similar direction. The latch member actuates the pusher plate to effect movement of the folding plate into folding position, the latch fingers then engaging the corresponding keeper to prevent upward movement of the lever 26. The actuating member, simultaneous with the movement of the latch member into keeper engagement, also urges the arm 38 in a direction to effectuate movement of the presser plate into pressing position, the roller 78 on the arm being yieldingly urged by spring 82 into engagement with the roller with the actuating member to thereby lock the actuating member in a locking position. After the folding and pressing operation is completed, only a slight force is necessary to urge the actuated member in a clockwise direction to effectuate a release of the folding and pressing mechanism.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. In a fabric edge folding device including a base plate having an opening therein, folding plates mounted for movement inwardly of the periphery of said opening, a pusher plate for moving said folding plates, a lever, and a forming plate mounted on said lever and movable therewith into edge forming position in said opening; a keeper in said folding device, and latch means pivotally mounted in said lever and

movable relative thereto to sequentially engage said pusher plate and said keeper and thereby lock said forming plate in its edge forming position, an arm and a presser plate mounted on said arm for movement therewith into and out of engagement with said forming plate when the latter is disposed in said opening, said latch means including means engageable with said arm to move said presser plate into engagement with said forming plate.

2. In a fabric edge folding device including a base plate having an opening therein, folding plates mounted for movement inwardly of the periphery of said opening, a pusher plate for moving said folding plates, a lever, and a forming plate mounted on said lever and movable therewith into edge forming position in said opening; a keeper in said folding device, and latch means pivotally mounted in said lever and movable relative thereto to sequentially engage said pusher plate and said keeper and thereby lock said forming plate in its edge forming position, an arm, a presser plate mounted in said arm for movement therewith into and out of engagement with said forming plate, manually operable means for moving said latch means into engagement with said keeper, and means in said arm manually operable means engageable with said arm for moving the presser plate into engagement with said forming plate.

3. The combination of claim 2 including means yieldingly urging said latch means out of engagement with said keeper, and means in said arm engageable with said manually operable means to releasably retain said latch in its keeper engaging position.

4. The combination of claim 3 wherein said forming plate is yieldably mounted on said lever.

5. In a fabric edge folding device including a lever actuated forming plate and an arm actuated presser plate, said arm and lever being movable towards each other into their respective edge folding and pressing positions, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper, to thereby lock said folding plates and forming plates in their edge folding position.

6. In a fabric edge folding device including a lever actuated forming plate and an arm actuated presser plate, said arm and lever being movable towards each other into their respective edge folding and pressing positions, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper to thereby lock said folding plates and forming plates in their edge folding position, cam means in said actuating member for moving said arm and presser plate into pressing position.

7. In a fabric edge folding device including a

lever actuated forming plate and an arm actuated presser plate, said arm and lever being movable towards each other into their respective edge folding and pressing positions, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper to thereby lock said folding plates and forming plates in their edge folding position, cam means in said actuating member for moving said arm and presser plate into pressing position, and spring means connecting said arm and pusher plate and yieldably urging said arm into engagement with said cam means to releasably retain said actuating member in its latching position.

8. In a fabric edge folding device including a lever actuated forming plate and an arm actuated presser plate, said arm and lever being movable towards each other into their respective edge folding and pressing position, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper to thereby lock said folding plates and forming plates in their edge folding position, cam means in said actuating member for moving said arm and presser plate into pressing position, and spring means connecting said arm and pusher plate and yieldably urging said arm into engagement with said cam means to releasably retain said actuating member in its latching position.

9. In a fabric edge folding device including a lever actuated forming plate and an arm actuated presser plate, said arm and lever being movable towards each other into their respective edge folding and pressing positions, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper to thereby lock said folding plates and forming plates in their edge folding position.

10 15 20 25 30 35 40

15 20 25 30 35 40

9. In a fabric edge folding device including a lever actuated forming plate and an arm actuated presser plate, said arm and lever being movable towards each other into their respective edge folding and pressing positions, a base plate having an opening therein between said lever and arm, folding plates movable inwardly of the edge of said opening, and a pusher plate for moving said folding plates into edge folding position; a latch plate mounted on said lever, a keeper in said base plate, and an actuating member pivotally mounted on said lever and movable into latching position to urge said latch member sequentially into engagement with said pusher plate and said keeper to thereby lock said folding plates and forming plates in their edge folding position, cam means in said actuating member for moving said arm and presser plate into engagement with said actuating member to releasably retain the latter in its latching position, means yieldingly urging said latch plate out of keeper engaging position, and cam means on said latch plate engaged by said actuating member when said latch plate is in keeper engaging position to urge said actuating member radially of its pivotal axis.
